UNITED STATES PATENT OFFICE.

THEODORE W. FOSTER, OF PROVIDENCE, RHODE ISLAND.

DESIGN FOR A BACK FOR MIRRORS.

No. 38,179.

Specification for Design.

Patented Aug. 21, 1906.

Application filed July 16, 1906. Serial No. 326,521. Term of patent 7 years.

To all whom it may concern:

Be it known that I, THEODORE W. FOSTER, a citizen of the United States, residing at Providence, in the county of Providence and State of Rhode Island, have invented a new, original, and ornamental Design for the Back of a Mirror, reference being had to the accompanying drawing.

The figure in the drawing is the back view of a mirror, showing my design.

I claim—

The ornamental design for the back of a mirror, as shown.

THEODORE W. FOSTER.
